UNITED STATES PATENT OFFICE.

GEORGE A. WEBER, OF NEW YORK, N. Y., ASSIGNOR TO THE WEBER RAIL-WAY JOINT MANUFACTURING COMPANY, OF NEW YORK, N. Y., A CORPORATION OF WEST VIRGINIA.

INSULATED JOINT.

SPECIFICATION forming part of Letters Patent No. 735,631, dated August 4, 1903.

Application filed March 4, 1903. Serial No. 146,229. (No model.)

To all whom it may concern:

Be it known that I, GEORGE A. WEBER, a citizen of the United States, and a resident of the borough of Manhattan, city, county, and State of New York, have invented certain new and useful Improvements in Insulated Joints, of which the following is a specification, accompanied by drawings.

This invention relates to rail-joints, but more particularly to insulated joints for railroad-rail sections; and the objects of the invention are to improve upon the construction of such joints and increase their strength and efficiency, with simplicity of parts which are not liable to get out of order.

Another object of the invention is to enable the joint to be made without insulation between the webs of the rails and those portions of the securing-bolts which pass through the webs of the rails, while a further object of the invention is to prevent short-circuiting of the rails by the wheels of a car.

Further objects of the invention will hereinafter appear; and to these ends the invention consists of an improved insulated joint for carrying out the above objects, embodying the features of construction, combinations of elements, and arrangement of parts, substantially as hereinafter fully described and claimed in this specification and shown in the accompanying drawings, in which—

Figure 1 is a transverse sectional view of the joint embodying the invention. Fig. 2 is a plan view of the same. Fig. 3 is a side elevation.

Referring to the drawings, A and B represent the ends of railroad-rail sections which are to be insulated one from the other. As shown in this instance, the rail ends are supported upon a suitable rail-chair C, which comprises the base or bridge plate D and the upright or bolt plate E, with the longitudinally-extending strengthening rib or fillet F at the juncture of the base and upright. Any suitable rail-chair may be utilized in this improved joint, and the invention is not limited to any particular kind of chair.

It has been found that when the faces of the rail ends are separated by thin posts of

insulating material, such as fiber, a short circuit between the ends of the rails may be occasioned by wheels of large diameter. The fiber not being sufficiently rigid will permit the periphery of the wheels to sink slightly below the surface of the rails, and thus produce a bridge between the rail ends to complete a circuit across the insulated gap. According to this invention a short section G of railroad-rail is included in the insulated joint and arranged between the ends of the rail-sections A and B. This short section of rail G is suitably insulated from the rail-sections A and B, and thus forms what may be termed a "dead" portion of the rail. According to this construction it will be seen that although a wheel may bridge across between either rail-section A or B and the section G a short circuit will not be occasioned. The ends A and B of the rail-sections, together with the section G, are suitably insulated from the base D of the rail-chair by the sheet H of insulating material, which is suitably maintained in position upon the chair. In this instance insulating-blocks I and J, which may be of wood, are arranged along the webs of the rail-sections A and B and along the web of the intermediate dead section G. The block I, as shown, is between the webs of the rails and the upright E of the angle-chair. The block J is shown at the other side of the joint, and outside of said block extends the metallic strengthening-bar K. The bar K in this instance is made continuous and extends across the joint.

The sheet H of insulation is extended upwardly between the insulating-block I, of packing or filling material, and the upright E of the angle-chair, so that when the parts of the joint are secured together by means of the bolts L the insulation H is securely clamped between the block I and the upright E.

Suitable bolts L extend through the portions of the joint and are provided with the heads O and nuts P. Suitable insulating-sleeves Q insulate the shank of the bolt from the upright E and the strengthening-bar K, while suitable insulating-washers R, as

shown, insulate the head O and nut P from the metallic portions of the joint. Metallic washers S may be arranged between the insulating-washers R and the head O and nut P, respectively.

According to this construction insulation is not needed between the shank of the bolt and the webs of the rails A and B and the web of the section G. Suitable insulating-
10 posts T, of any desired insulating material, as shown, may be inserted between the faces of the rail ends A and B and the faces of the short section G.

It will be seen that according to this construction all the bolt ends and heads are insulated, so that current cannot pass from rail to rail through either the chair or metal bar K without passing insulation at two points, because of there being insulation between
20 both the rail ends and the bar and chair.

This double insulation, though preferred, is not, therefore, essential. According to this invention it will be seen that a greater dead space is obtained between the ends of the
25 rails, or, in other words, a longer portion of insulation is obtained. The insulated section G, comprising a portion of a railroad-rail, is rigid and strong and firmly supports the passing wheels of an engine or car.

30 I do not herein claim, broadly, an insulated rail-joint of the character described embodying the strengthening strap or band extending across the joint opposite the upright of the chair, as insulated joints embodying this

35 feature in various forms are claimed in my copending applications, Serial Nos. 63,124 and 63,125, filed June 4, 1901; No. 87,053, filed December 24, 1901; No. 124,193, filed September 20, 1902, and No. 133,770, filed December 3, 1902.

Obviously some features of this invention may be used without others, and the invention may be embodied in widely-varying forms.

45 Therefore, without limiting myself to the construction shown and described nor enumerating equivalents, I claim, and desire to obtain by Letters Patent, the following:

50 1. A rail-joint, comprising a suitable rail-support or bridge-plate, rail ends supported thereon, the base of at least one rail being in-

sulated therefrom, and there being a plurality of insulating-breaks between the ends of the rails, insulating-blocks extending along the webs of the rails, and insulated bolts for securing the parts of the joint together, for substantially the purposes set forth. 55

2. An insulated joint, comprising an angle-chair, rail ends supported thereon and insulated therefrom, an insulated section of rail between the ends of said rail-sections, and insulated bolts for securing the parts of the joint together, for substantially the purposes set forth. 60

3. An insulated joint, comprising an angle-chair, rail ends supported thereon, the base of one being insulated therefrom, blocks of insulating material extending across the joint along the webs of the rails, a section of rail between the rail ends and insulated therefrom, a metal strengthening-bar arranged along one of said insulating-blocks and extending across the joint, and insulated bolts for securing the parts of the joint together, for substantially the purposes set forth. 65

4. An insulated rail-joint, comprising an angle-chair having a base and an upright, rail ends supported thereon, the base of at least one rail being insulated therefrom, an insulated section of rail between the ends of said rail-sections, insulating-blocks extending across the joint along the webs of the rails, and insulated bolts for securing the parts of the joint together, for substantially the purposes set forth. 70

5. A rail-joint, comprising a suitable rail-support or bridge-plate, rail ends supported thereon, the base of at least one rail being insulated therefrom and there being a plurality of insulating-breaks between the ends of the rails, means for maintaining the rail ends in alinement, and insulated bolts for securing the parts of the joints together, for substantially the purposes set forth. 75

In testimony whereof I have signed this 95 specification in the presence of two subscribing witnesses.

GEORGE A. WEBER.
